Primary Examiner — Marissa J Cash*Assistant Examiner* — Rebecca Tsehay*(74) Attorney, Agent, or Firm* — BakerHostetler(57) **CLAIM**

The ornamental design for a personal vaporizer, as shown and described.

DESCRIPTION

FIG. 1 is a front perspective view of a personal vaporizer; FIG. 2 is a bottom rear perspective view thereof.

FIG. 3 is a front view thereof.

FIG. 4 is a rear view thereof.

FIG. 5 is a left view thereof.

FIG. 6 is right view thereof.

FIG. 7 is a top view thereof.

FIG. 8 is a bottom view thereof; and,

FIG. 9 is a top front perspective view shown with a cartridge installed for environmental purposes.

The broken lines in FIGS. 2, 7, and 8 depict portions of the personal vaporizer that form no part of the claimed design; the broken lines in FIG. 9 are for environmental purposes that form no part thereof.
